UNITED STATES PATENT OFFICE.

MAHLON L. DUNBAR, OF AKRON, OHIO, ASSIGNEE TO THE REX EXTINGUISHER COMPANY, INC., OF AKRON, OHIO, A CORPORATION OF OHIO.

CHEMICAL FIRE-EXTINGUISHER.

1,158,904.

Specification of Letters Patent.

Patented Nov. 2, 1915.

Application filed January 19, 1915. Serial No. 3,112.

To all whom it may concern:

Be it known that I, MAHLON L. DUNBAR, a citizen of the United States, residing at Akron, in the county of Summit and State 5 of Ohio, have invented new and useful Improvements in Chemical Fire-Extinguishers, of which the following is a specification.

This invention relates to improvements in fire extinguishers of the hand or portable 10 type, and particularly to an extinguisher for use in automobiles, motorboats and wherever a hand extinguisher is sufficient to meet requirements.

One object of the invention is to provide 15 an extinguisher in which the extinguishing agent, such as carbon tetrachlorid, is designed to be discharged by compressed air, and wherein the extinguishing agent and air are stored in separate reservoirs, whereby 20 greater safety and other manifold advantages and conveniences are gained.

Another object of the invention is to provide simple, reliable and efficient valve mechanism for simultaneously governing the 25 discharge of the extinguishing agent and the supply of compressed air in amounts regulated by the amount of the extinguishing agent discharged, whereby waste of the extinguishing agent and air is avoided and better control in directing the discharge of the extinguishing agent afforded.

A still further object of the invention is to provide a fire extinguisher which is simple 35 of construction and inexpensive of production, and which embodies means for indicating the amount of extinguishing liquid and compressed air contained therein at any time, and for conveniently replenishing the reservoirs as occasion requires.

40 The invention consists of the features of construction, combination and arrangement of parts herein fully described and claimed, reference being had to the accompanying drawing in which:

45 Figure 1 is a side elevation of the extinguisher indicated as fully charged and with the valves closed. Fig. 2 is a vertical longitudinal section of the same, showing the valves open and the plunger at the limit of its discharge movement. Fig. 3 is a sectional elevation, looking toward the extinguisher at right angles to the view shown in Fig. 1, and showing the parts 50 as illustrated in Fig. 1.

In carrying my invention into practice, I 55 provide an extinguisher comprising a reservoir 1 for the extinguishing agent or liquid and a reservoir 2 for a suitable pressure discharge medium, such as compressed air.

The reservoir 1, as shown; includes an 60 inner tube or lining 3 of glass and an outer casing 4 of metal, closely embracing and reinforcing the glass tube. The casing 4 is provided with a longitudinally extending slot (one or more) 5, through which the glass 65 tube or lining may be viewed so that the amount of the extinguishing liquid contained at any time within the casing may be determined. The exposed portion of the tube 3 may be provided with graduations 70 for convenience in determining the exact amount, if desired.

The casing 4 is externally threaded at its front and rear ends to receive flanged heads or closure caps 6 and 7, while the reservoir 75 2, which is made of suitable metal, is also externally threaded at its ends to receive flanged closure heads or caps 8 and 9. The gaskets 10, of lead or other suitable material, are interposed between the parts 3 and 4 80 and caps 6 and 7 to form air and liquid tight joints, while similar gaskets 11 are interposed between the reservoir body 2 and caps 8 and 9 for the same purpose.

In practice, the heads or caps 7 and 8 may 85 be integral with each other and connected by a portion 12 forming a valve casing, which is designed to establish communication through aligned ports 13 and 14 between the air and extinguishing agent reservoirs 90 for the purpose of discharging the liquid under a desired pressure. Instead of threading all of the heads or caps in position, some of them may be brazed to the reservoir bodies, it being only necessary to make sufficient of the parts removable for the purpose 95 of assemblage, disassemblage, cleansing and repairs, the main purpose being to make the reservoirs strong enough to effectually withstand the internal pressures.

100 As shown the reservoir 1 is provided with a discharge nozzle 15 integral with the cap 6, and the valve casing 12 and the said nozzle are properly bored or chambered to receive tapered rotary plug valves 16 and 17, 105 said chambers being closed by screw caps 18 and 19, and said valves having stems 20 and 21 projecting externally through said caps

- and provided with crank arms 22 and 23 connected by a link 24, whereby said valves are adapted to be opened and closed in unison and in coördination with each other.
- 5 The stem of the valve 20 is also provided with an operating handle or lever 25 whereby the valves may be conveniently opened and closed. The reservoir 2 is provided with a gage 26 whereby the amount of air 10 stored under pressure therein may be determined at all times. The reservoir 1 is adapted to be charged or replenished with the extinguishing liquid through an inlet 27 in the cap 6, which inlet is normally closed by 15 a plug 28, while the cap 9 of the reservoir 2 is provided with a suitable construction of check valved inlet 29 for the supply of compressed air thereto from any suitable source.
- 20 Arranged for operation within the reservoir 1 is a discharge plunger 30. This plunger comprises a hollow body, of a diameter to snugly fit the interior of said reservoir, said body having a concaved inner or 25 rear face 31 for the proper impingement and concentration of the air thereon. The interior of the hollow plunger is filled with a suitable sealing and lubricating liquid 32, such as glycerin, this substance being used 30 because of its non-drying quality, and its lubricating efficiency, and also because it is unaffected by the preferably employed extinguishing liquid, carbon tetrachlorid.
- The body wall of the plunger is formed 35 with an annular groove 33 communicating with the interior of the plunger body through an annular series of fine perforations 34, through which the glycerin gradually discharges into the groove in which 40 it is retained, thereby lubricating the surfaces of the plunger and reservoir and at the same time forming a seal by which leakage of the air past the plunger into the liquid containing space of the reservoir will 45 be effectually prevented. The device may be provided at a suitable point with a bracket 35 having a slot of a key-hole-shape or other suitable form, by which the device when not in use may be suspended from a 50 wall or other suitable support.
- When the device is charged for use, it will be understood that the hollow plunger is arranged behind the column of extinguishing liquid and between the same and the 55 cap or head 7, and that the valves 16 and 17 are closed to prevent the escape of air from one reservoir to the other and the leakage of liquid from the extinguishing liquid reservoir outward through the nozzle. When, 60 however, a fire breaks out and it is desired to extinguish the same, the device is removed from its support and held in the hands of the operator so as to point the nozzle 15 in the direction of the blaze and the 65 valve handle 25 is then swung forwardly to open the valves to a greater or less degree, whereby a greater or less quantity of the extinguishing liquid may be discharged from the nozzle against the flames, the construction thus being such that only the 70 amount of liquid necessary to extinguish the flames need be discharged, thus preventing waste of the extinguishing substance. As the extinguishing liquid and pressure fluid are also kept separate, it is evident that the 75 device will always be in condition for use up to the time its contents are fully discharged, and that contamination or deterioration of the extinguishing liquid can not possibly occur. As the hollow plunger, 80 which forces the liquid outward under the action of the compressed air, is lubricated by an element which is at the same time a sealing medium, and which will last for an indefinite period without gumming or drying, it is evident that the liquid reservoir will be at all times maintained in a highly efficient state or condition to perform its intended function. By making the reservoirs 85 separate and independent, it is furthermore 90 evident that the liquid reservoir need not have to withstand an extremely high pressure with liability of explosion, leakage or other objections, while at the same time the provision of the controlling valves enables 95 thorough coördination between the amount of fluid pressure supplied and the amount of extinguishing liquid discharge to be governed and controlled to an exact degree. In 100 order to hold the valves positively seated against leakage, to render them self-grinding and proof against leakage, and to insure their certainty of adjustment as against leakage, I preferably make each valve of less length than its chamber or casing and 105 hold the valve under the pressure of a spring 36 whose tension may be regulated by the cap 18 or 19, by which the valve will always be held snugly within its seat.
- It will be seen from the foregoing description that my invention provides a hand or portable fire extinguisher, by which an extinguishing liquid of the character set forth, to wit, carbon tetrachlorid, may be 110 stored and employed in an effective manner, and that a simple and compact form of extinguisher is provided which is especially 115 designed for use upon automobiles, motor-boats and other craft and elsewhere, to enable a fire, especially one starting from the 120 ignition of gasoline or other volatile hydrocarbons or fuels, to be readily, easily and quickly extinguished.
- Other advantages and conveniences will be apparent from the illustrated disclosure 125 and foregoing description to those versed in the art.
- I claim:—
1. A fire extinguisher including a reservoir for an extinguishing liquid, a reser-

130

voir for a fluid pressure medium arranged in axial alinement with the first-named reservoir, a connection uniting said reservoirs and provided with a passage for the flow of 5 the fluid pressure means from the fluid pressure reservoir to the liquid reservoir, an outlet leading from the liquid reservoir, controlling valves in said connection and outlet, a plunger within the liquid reservoir 10 between the source of pressure and the liquid, and means for simultaneously and coördinately operating said valves.

2. A fire extinguisher including liquid and fluid pressure reservoirs arranged in 15 axial alinement, a valved outlet from the liquid reservoir, a valve connection between said reservoirs, a floating piston within the liquid reservoir between the liquid and the source of pressure, said piston being provided with means for lubricating its 20 periphery and forming a sealing connection between the same and the wall of the liquid

reservoir, and means for simultaneously and coördinately adjusting the valves.

3. A fire extinguisher comprising a reservoir for an extinguishing liquid, said reservoir having a discharge outlet, means for supplying fluid pressure to said reservoir, valved controlled means governing the discharge of liquid from the liquid reservoir 25 and the supply of fluid pressure to said reservoir, and a plunger within the reservoir comprising a hollow body having an annular groove and perforations connecting said groove with the interior of said 30 body, the latter having a charge of a lubricating and sealing liquid.

In testimony whereof I affix my signature in presence of two witnesses.

MAHLON L. DUNBAR.
